(57) **CLAIM**

The ornamental design for a housing for electronic tag, as shown and described.

DESCRIPTION

FIGS. 1 through 4 are top perspective views of a housing for electronic tag showing the new design according to one embodiment.

FIG. 5 is a top view of the housing for electronic tag of FIG. 1.

FIG. 6 is a bottom view of the housing for electronic tag of FIG. 1.

FIG. 7 is a left view of the housing for electronic tag of FIG. 1.

FIG. 8 is a right view of the housing for electronic tag of FIG. 1.

FIG. 9 is a rear view of the housing for electronic tag of FIG. 1; and,

FIG. 10 is a front view of the housing for electronic tag of FIG. 1.

All of the broken lines in the accompanying drawings illustrate environmental structure and form no part of the claimed design.
